UNITED STATES PATENT OFFICE.

WINTON G. MIDDLETON, OF OAKLAND, CALIFORNIA, ASSIGNOR TO MERGENTHALER LINOTYPE COMPANY, A CORPORATION OF NEW YORK.

LINE-CASTING MACHINE, &c.

957,433.

Specification of Letters Patent. Patented May 10, 1910.

Application filed April 15, 1909. Serial No. 499,052.

To all whom it may concern:

Be it known that I, WINTON G. MIDDLETON, of the city of Oakland, county of Alameda, and State of California, have invented a new and useful Improvement in Line-Casting Machines, &c., of which the following is a specification.

My invention relates to line casting machines of the general character represented in Letters Patent of the United States 436,532, for producing printing bars or slugs, each bearing the type characters to print a line. In these machines a composed line of matrices representing the characters to appear on one slug is presented temporarily to the face of a slotted mold, which is mechanically filled with molten type metal, which solidifies in the form of a slug or bar, having on the front edge the characters formed by the matrices. After the casting action the disk is turned to present the mold opposite a vertical horizontal ejector blade, which advances horizontally through the mold, driving the upright slug therefrom into a receiving galley at the front. It is a common practice to provide these mold wheels with two or more molds the slots in which differ in size, so that either mold may be brought into action at will for the production of the slugs required, the change from one mold to the other being accompanied by a corresponding change or substitution of ejector blades.

The object of my invention is to adapt the machine to produce at will slugs of different lengths without the necessity for changing the ejector blade, the one blade being adapted to deliver both long and short slugs. To this end I provide the rotary mold wheel with two alternately usable molds having slots of equal length, one of the slots being divided by a partition in order that it may produce two short slugs. In connection with these two molds I use an ejector slotted or divided in such manner as to straddle the partition and deliver from the divided mold the two short slugs formed therein. The same blade will deliver the long slugs from the continuous mold. I also provide means whereby the two short slugs formed in the respective ends of the one mold are separated and delivered to different points.

The mold stands in a vertical position while the slug is being delivered.

With the exception of the parts herein-

after described the machine may be in all respects of ordinary construction.

In the drawings: Figure 1 is a horizontal section through the casting and ejecting mechanism of a Mergenthaler machine with my improvements incorporated therein. Fig. 2 is a front elevation of the mold disk and molds. Fig. 3 is a section on the line 3-3 Fig. 1. Fig. 4 is a side elevation of the parts shown in Fig. 1. Fig. 5 is a side view of the ejector blade.

Referring to the drawings, A represents the vertical mold wheel or disk journaled to a horizontal supporting slide, B.

C, C' represent the two slotted molds mounted on opposite sides of the disk, so that the rotation of the latter will serve to present either mold in operative relation to the other parts as usual.

The mold C has a continuous slot from end to end, and is adapted for the production of long slugs. The mold C' is divided by a partition, c, into two sections, adapted to produce short slugs—one or both of which may be used. The molds may be constructed and the partitions inserted and secured in any appropriate manner.

D represents the horizontal ejector blade by which the slugs are driven forward out of the molds. This blade is made of sufficient width to fill or substantially fill the long mold, in order to eject long slugs therefrom. Instead of being made in one solid piece as usual, it is divided or slotted longitudinally in such manner as to straddle the partition c. It will be seen, therefore, that the one blade will serve to eject the single long slug from one mold, or the two shorter slugs from the divided mold, as required.

E, E' are the two knives between which the slugs are delivered when ejected from the mold.

F is the galley in which the slugs are received. The galley is in position to receive all the long slugs and the lower one of the short slugs directly from the mold.

G is a spring pressed plate forming one side of the throat through which the slugs pass, between the knives and the galley. This plate instead of being made continuous as usual is recessed or cut away on one side at the upper part as shown at g in Fig. 4, the opening being of such size and so located that while the slugs delivered from the

lower part of the divided mold will be held by the blade and continued in their course to the galley, the slugs cast in the upper part of the mold will be compelled to escape laterally through the opening g . In order to secure this delivery the spring g' is seated in the throat or passage as shown to act against the upper slugs and deflect them. A chute or guide plate g^2 may be used to direct them downward to a galley or receptacle of any kind.

While I have shown a slotted ejector blade it is to be understood that a blade composed of two or more independent sections may be used, these sections to be adjustably or detachably connected with the operating slide in any suitable form, various connections suitable for the purpose being known in the art.

Having described my invention, what I claim is:

1. In a line casting machine, a rotary wheel provided with two alternately operative molds of equal length, one divided and the other undivided, in combination with a divided ejector adapted to enter both molds, a receiving galley in position to receive both long and short slugs, and means for directing one short slug of each pair away from the galley.

2. In a line casting machine, a mold wheel provided with two alternately usable molds, one having a continuous and the other a divided slot, in combination with a divided ejector adapted to enter both molds, and means for separating the two slugs delivered from the divided mold.

3. In a line casting machine the combination of two alternately usable molds, one continuous and the other divided in length, an ejector adapted to pass through both molds, a galley adapted to receive the long slugs, and also the lower short slugs, means for guiding said slugs from the mold to the galley, and an automatic device in the path of the outgoing slugs to change the path of the upper short slugs only.

4. In a line casting machine, the combination of molds for producing long and short slugs, means for delivering the slugs from the molds, and guiding mechanism adapted to direct all long slugs in a common path and direct short slugs in different paths.

5. In a line casting machine, the combination of a mold, means for delivering slugs, means for guiding the delivered slugs, and a spring deflector, g' , arranged to divert the outgoing slugs laterally from the path in which they left the mold.

6. In a line casting machine, the combination of a divided mold adapted to form two slugs, an ejector adapted to deliver all slugs therefrom, a slug receiving galley, and guiding devices, located between the mold and the galley and adapted to deliver certain of the slugs to the galley and others in a different path.

In testimony whereof I hereunto set my hand this 9th day of February, 1909, in the presence of two attesting witnesses.

WINTON G. MIDDLETON.
